[57] CLAIM

The ornamental design for a hermaphroditic coupling for anatomical thermal system, as shown and described.

DESCRIPTION

FIG. 1 is a perspective view of a hermaphroditic coupling for anatomical thermal system, showing my new design, in connected condition;

FIG. 2 is a perspective view of one half of the coupling; FIG. 3 is another perspective view of one half of the coupling;

FIG. 4 is a top plan view of one half of the coupling; FIG. 5 is an end view of one half of the coupling; FIG. 6 is the opposite end view of one half of the coupling;

FIG. 7 is a side view of one end of the coupling; and FIG. 8 is the other side view of one half of the coupling.

The opposite sides of Figs. 1-4 are identical to that shown.
